UNITED STATES PATENT OFFICE

ANDREW J. MONROE AND GEORGE W. MONROE, OF ARTHUR, ILLINOIS

LIFTING ATTACHMENT FOR ROAD GRADERS

Application filed September 6, 1929. Serial No. 390,773.

The object of this invention is to provide for the adjustment and lifting movement of the blade of a road grading machine, this blade being carried below an approximately horizontal frame adapted for tilting movement and under the control of operating devices on both sides of the machine.

A further object is to provide operating means including hand controlled worm gearing, a longitudinal shaft on each side, and a link having special connection with the shaft and with the tiltable frame controlling the angular position of the blade.

A further object is to provide special means for mounting and adjusting a spring adapted to aid the operator in lifting the tiltable frame and blade when the latter is to be elevated from normal operative position, either momentarily or when a particular portion of the work under way has been finished.

With the foregoing and other objects in view, the invention consists in the novel construction and arrangement of elements disclosed, it being understood that modifications may be made within the scope of the claims without departing from the spirit of the invention.

In the drawings forming part of this application:—

Figure 1 is a view of the machine in side elevation.

Figure 2 is a top plan view.

Figure 3 is a view in vertical transverse section on line 3—3 of Figure 1.

Figure 4 is also in vertical transverse section on a plane passing thru the gear housings near the driver's seat.

Figure 5 is a detail in section showing means for adjusting the lifting spring which appears prominently in Figures 1 and 2, and aids the operator in elevating the blade.

The blade serving the usual purpose in a road grading machine, is designated 10, and is illustrated as being provided with a longitudinal re-inforcing element 11, the blade being supported by means of an approximately U-shaped frame 12, the rear lower ends of which are connected with element 11 at the points 11'. Other retaining means are

shown conventionally at 14. The U-frame is secured to a horizontal frame adapted to be tilted or inclined angularly in different directions, by means of the particular mechanism now to be described. This frame may be of substantially A form, and the side members thereof are designated 15, the forward end of the frame being mounted for universal movement, as shown at 16. The connection here is directly or indirectly with the forward truck, including the axle 17 and wheels 18. These wheels are to be mounted for tilting movement on a horizontal axis, as shown more or less conventionally at 19, the construction at this point being disclosed in my co-pending application Serial Number 390,772, and not claimed in the present case.

The A-shaped frame also includes transverse angle braces or the like such as those designated 20 and 21, and diagonal braces 22, and the tiltable or angularly movable frame including the elements 15 is to be supported and controlled in the particular manner described and claimed.

The main frame includes the side members 24, and this frame pivotally supports the A-shaped frame by means of links such as links 25, secured at 26, at their lower ends, and pivotally secured at 27 by means of L-shaped devices 28 which in turn are pivoted at 29 to crank arms 30, on the horizontal and longitudinally extending shafts 31. These shafts are mounted in suitable bearings, and are controlled thru suitable gearing by a plurality of hand wheels.

At the rear of the machine is an operator's platform 33, and supported thereon by any suitable means shown conventionally at 34 are housings 35, for the gear mechanism. Each shaft 31 mounts a worm wheel 36, keyed on the shaft, and controlled by worm 37 on shaft 38. Each shaft 38 carries rigidly thereon a hand wheel such as 40, and these wheels last named may be positioned as indicated in Figures 2 and 4, so that they will be at the right and left of the operator, whose seat is shown at 41 in Figure 1.

In view of the fact that the links 25 are secured as shown in Figure 3, either side of the frame including elements 15, is tiltable

independently of the other side, movement taking place at the same time at the rear portion of the horizontal tiltable frame, and at the universal connection shown conventionally at 16.

Extending between the side members 15 of the A-shaped frame, tiltable as described, is a horizontal threaded rod or the like designated 43, this rod having its end portions suitably mounted with reference to said members 15 of the frame, and a threaded device 44 including an eye portion 45 is adjustable to various positions on element 43, an arm 46 passing thru the member 45 and having connection with the tiltable frame, at the point 47. This construction permits of the retention of the lower frame just described, in an adjusted position, that is in the position of Figure 3 or in a position in which it extends laterally to a greater degree on one side of the stationary frame 24 than on the other.

The threaded element or screw 43 is controlled by means of gearing including elements 50 and 51 and shaft 52, under the control of the wheel or other hand operated device 53, which may be positioned as shown in Figure 1.

A further important feature of construction is that relating to the mounting of a lifting spring, aiding the operator in the elevation of the blade 10, when the latter is to be thrown out of use temporarily or after the work under way has been finished.

The spring is connected forwardly to an eye bolt 55, the spring being designated 56, and extending rearwardly and upwardly as the arrangement is shown in the drawings,—this spring having connection at the rear portion thereof with a flexible device or cable 57 passing over a tension pulley or the like 58. The cable 57 extends thence in a downward direction, and is connected with the lower horizontal tiltable frame including elements 15, by means of any suitable device such as that shown in Figure 3 and designated 59. This device is secured to one of the transverse elements of the frame last referred to.

In order to adjust the pulley 58, we provide particular mounting means including a bracket, U-hanger or the like designated 60, and having connected therewith an eye member 61 which is engaged by an eye portion 62 on the lower end of screw 63. This screw passes thru a stationary bracket 64, and the screw is surrounded by a spring 65, positioned above the bracket 64, and between the latter and the hub portion of the hand wheel 66 having threaded connection with the screw 63. Adjustment is thereby secured in an obvious manner, and the device just referred to will be within reach of the operator.

In order to disclose a complete machine we have also shown a hand operated device for controlling the tilting or leaning movement

of the front wheels. A crank 70 is carried by one end of shaft or the like 71, and extends forwardly to point 72, where it has or will have operative connection with the mechanism shown conventionally at 19 for controlling the leaning movement of the front wheels. This mechanism thus controlling the wheels is described in the aforesaid pending application, Serial No. 290,772, filed September 6, 1929. Provision is made for a similar leaning wheel movement at the rear of the machine, and the construction is employed for preventing side-wise movement of the machine when the latter is operated on transverse grades or sloping ground.

What is claimed is:—

A lifting device for road graders including a main frame supported by wheels, an auxiliary frame movably mounted on the main frame, a blade carried by the auxiliary frame, means to raise and lower the blade, a spring secured to the main frame, a flexible element connecting the spring to the auxiliary frame, a bracket secured to the main frame and having an opening, an operating rod extending through said opening, a pulley carried by the rod and having the flexible element trained thereover, a hand wheel threaded to said rod and adapted to be adjusted towards and from the bracket, and tension means between the hand wheel and the bracket.

In testimony whereof we affix our signatures.

ANDREW J. MONROE.
GEORGE W. MONROE.
